Application October 7, 1942, Serial No. 461,181

10 Claims. (Cl. 57—18)

This invention relates to tensioning apparatus and more particularly to an apparatus for applying a constant tension to a web being drawn from a spool rotating about the axis of a constantly advancing element to wrap the web uniformly on the element.

It is an object of the present invention to provide a simple and highly effective apparatus for maintaining the desired tension in an element being applied to a second element.

In accordance with one embodiment of the invention, an apparatus is provided for maintaining constant tension in a web being wound from a pad or roll mounted concentrically of a constantly advancing cable onto said cable. The constant tension is effected by utilizing the speed-torque characteristic of an induction type torque motor to apply, through a planetary differential mechanism, a torque tending to rotate a spider on which the feed pad or roll is mounted in a direction opposite to the direction in which the motor which supplies power to advance the cable also tends to drive the pad through the differential mechanism. A high resistance induction type torque motor is provided so that the motor will have the proper speed-torque characteristic to apply a constant tension to the strand.

A complete understanding of the invention may be had by reference to the following detailed description of one embodiment thereof, when considered in conjunction with the accompanying drawing, wherein

Fig. 1 is a diagrammatic illustration of a preferred embodiment of the invention, and

Fig. 2 is a graphic illustration of the speed-torque curve of an induction type torque motor suitable for use in the present invention, showing the portion of said curve utilized in practicing the invention.

Referring to the drawing wherein the invention is illustrated as applied to a tension device for controlling the tension of a paper web 5 being wrapped spirally about a cable 6, it will be seen that the paper web 5 is drawn from a pad 7 mounted concentrically with respect to the cable 6. The cable, about which the web 5 is to be wrapped, is fed from left to right from any suitable supply source (not shown) by a capstan 8. Power for driving the capstan 8 is supplied by a main drive motor 9 which drives a chain 10 in the direction indicated by the arrow 11. The chain 10 engages and drives a sprocket 12 fixed to a shaft 13 upon which there is also fixed a sprocket 14. A chain 15 driven by the sprocket

14 drives a sprocket 16 fixed on a shaft 17 carrying a second sprocket 18. The sprocket 18 engages and drives a chain 19 which in turn drives a sprocket 20 on a driving shaft 21 of a speed reducer 22, the driven shaft of which has the capstan 8 fixed to it. Thus the cable 6 is advanced through the apparatus at a predetermined speed by the motor 9 at a fixed ratio to the speed of the motor 9.

10 Intermediate the sprockets 12 and 14 on shaft 13 there are fixed a pair of sprockets 30 and 31. The sprocket 31, through a chain 33, a sprocket 34 and a variable speed apparatus 32, which may be of any suitable type well known in the art, drives a sprocket 35 at a predetermined constant speed. A drive chain 36 interconnects the sprocket 35 and a sprocket 37 fixed on a hollow shaft or sleeve 38 on the other end of which there is positioned a ring gear support 39. Attached to the ring gear support 39 is an internally toothed ring gear 40 which meshes with a pair of planetary gears 41 and 42 mounted for free rotation on a spider 43. The spider 43 is mounted on a shaft 44 the axis of which coincides with the axis of a shaft 45 having a sun gear 46 and a sprocket 47 fixed at its opposite ends. The sun gear 46 meshes with the two planetary gears 41 and 42 and the sprocket 47 is engaged by a chain 48 which engages the drive sprocket 49 of a high resistance induction type torque motor 50.

At its end opposite the end which supports the spider 43, the shaft 44 carries fixed to it a sprocket 60 for driving a chain 61 which engages and drives a sprocket 62 fixed to the peripheral surface of a hollow shaft 63 through which the cable 6 is drawn by the capstan 8. The right end of the shaft 63, as seen in Fig. 1, supports and drives the pad 7 and the shaft is surrounded 40 throughout part of its length by a sleeve 64 driven in the direction indicated by arrow 65 by a sprocket 66 mounted on the outer surface of the sleeve 64 and driven by a chain 67 which is in turn driven by the sprocket 30 at a constant rate of speed. The sleeve 64 carries a flange member 68 on which are supported a pair of freely rotatable guide rollers 69 and 70 which guide the web of paper 5 drawn from the pad 7 and which determine the angle at which the web 5 is wrapped about the cable by the ratio of their speed of rotation bodily about the axis of the cable to the speed at which the cable is fed by capstan 8.

Inasmuch as induction type torque motors 55 have a known speed-torque characteristic which

is dependent on the resistance value of the secondary circuit of said motors, a motor 50 may be chosen having a resistance in its secondary circuit such that its speed torque curve is as shown diagrammatically in Fig. 2. That is, a motor may be chosen which has a torque of between 45 and 50 inch-pounds, at 0% of synchronous speed and which has zero torque at 100% of synchronous speed. The torque output of such a motor will, as indicated, vary at a known rate with the variation in speed thereof if the applied voltage is maintained at a constant value.

In the operation of the apparatus as described hereinbefore, power being supplied to the main driving motor 9 and to the induction type torque motor 50 will result in the capstan 8 being driven at a predetermined rate of speed through the speed reducer 22 which rate of speed is directly proportional to the rate of speed of the flange member 68 carrying the guide rollers 69 and 70. However, since it is desired to drive the pad 7 at a rate of speed different from the speed of the flange member 68, the variable speed reducer 32 will tend to drive the pad 7 through the planetary gear system at a rate of speed controlled by the speed reducer 32. Since it is practically impossible to control the speed of operation of the pad 7 with sufficient accuracy by a direct drive, some braking effect must be provided in order to maintain the proper tension in the web of paper 5. The variable speed apparatus 32 will drive the ring gear 40 in a direction opposite to the direction which the motor 50 tends to drive the sun gear 46. Since the motor 9 is appreciably stronger than the motor 50, the motor 50 will be driven counter to its normal direction of rotation due to the planetary gear connection between it and the speed reducer 32. The variable speed apparatus 32 being set to drive its output sprocket 35 at a selected constant speed the decrease in the size of the pad 7 due to the paper web 5 being drawn from it will be compensated for by the induction type torque motor 50 which will be driven faster in a reverse direction to its direction of normal rotation through the differential mechanism as the size of the pad 7 decreases. Correspondingly the torque output of the induction type motor 50 will drop from approximately 35 inch-pounds to approximately 30 inch-pounds as the torque motor is driven in reverse at an accelerated speed from approximately 60% to approximately 70% of synchronism in reverse.

In this manner, as the pad 7 decreases in size due to the removal of the web of paper therefrom and its application to the cable 6, the pad 7 will be driven faster.

If the cable 6 to which the web 5 is being applied is of other than circular cross section, the speed of the pad 7 will vary and the consequent speed of the motor 50 will also vary to maintain the tension in the web constant. It has been found that a substantially constant tension will be maintained in the web 5 when an oval cable 6 is wrapped with a web of paper 5 and thus the torque of the motor 50 will vary within the range indicated in Fig. 2 not constantly but will increase and decrease continuously while gradually decreasing in very small increments to maintain the tension constant.

While the torque motor 50 has been described as exerting a variable number of inch-pounds of torque as it varies from synchronous speed, it will be understood that, depending on the size of the pad 7 and the ratios of the various sprock-

ets described hereinbefore one to another, this braking effect may be varied and it is only necessary to choose a torque motor having proper resistance in its secondary circuit and to utilize the proper portion of its speed torque curve for control purposes in order to provide a tension in the web 5 within the desired limits.

If it is desired to vary the tension in the web 5 the variable speed apparatus may be changed so that a different portion of the speed torque curve of the motor 50 be effective. For example, that portion between the dotted lines designated "full pad" and "empty pad" may be selected. The provision of the variable speed apparatus 32 permits adjustment of the tension on the web 5 while the entire apparatus is operating. Such adjustment may be desirable when unusual stresses are applied to the web, such as may occur when the apparatus is started or stopped.

What is claimed is:

1. A tension apparatus comprising a rotatable takeup member for strand material, means for applying a wrapping to said strand including means for supporting a supply of said wrapping concentrically with respect to the strand, a variable speed reducing mechanism for supplying power tending to rotate said means for supporting the supply of wrapping, a common motor for supplying power to drive the means for supplying power to the takeup means and the speed reducer, a torque motor, a planetary gear mechanism interconnecting the speed reducer and the support for the wrapping, and means for controlling the effectiveness of the planetary gear mechanism under control of the torque motor.

2. An apparatus for applying tension to strand material comprising a rotatable member for holding a supply of strand material, means for withdrawing strand material from said rotatable member including a differential gear having a power input and a power output, said power input being mechanically coupled in fixed ratio to said means for withdrawing the strand, and a torque motor connected to said power output to be driven thereby to maintain a constant tension on the strand.

3. A tensioning apparatus comprising a rotatable support for a supply of material, means for withdrawing said material from the supply, means for applying a braking force on said support to restrain the withdrawal of material from it, comprising a differential gear mechanism for transmitting power to rotate the support, a torque motor for applying a torque to said mechanism, and a connection between said withdrawing means and the differential mechanism for supplying driving power to the differential mechanism and the torque motor.

4. A tensioning apparatus comprising a rotatable support for a supply of material, means for withdrawing said material from the supply, means for applying a braking force on said support to restrain the withdrawal of material from it, comprising a differential gear mechanism for transmitting power to rotate the support, a torque motor for applying a torque to said mechanism, and a driving connection for directly coupling the withdrawn means to the differential mechanism to drive the differential mechanism and through the differential mechanism to drive the torque motor.

5. A tensioning apparatus comprising a rotatable support for a supply of material, means for withdrawing said material from the supply, means

for applying a braking force on said support to restrain the withdrawal of material from it, comprising a differential gear mechanism for transmitting power to rotate the support, a torque motor for applying a torque to said mechanism, and a driving connection for directly coupling the withdrawing means to supply driving power to the differential mechanism and through the differential mechanism to drive the torque motor counter to its normal driving direction.

6. An apparatus for applying tension to strand material, comprising a rotatable member for holding a supply of strand material, means for withdrawing strand material from said rotatable member, means for restraining said rotatable member including differential gear mechanism having two power inputs and one power output, a torque motor tending to drive one of said power inputs, a positive driving connection between the withdrawing means and the other power input, and means interconnecting the power output and the rotatable support.

7. The combination with a rotatable support for holding a supply of flexible material wound thereon, of a positively driven means for withdrawing material from said supply, means restraining movement of said rotatable supply including a torque motor, a differential gear mechanism having a power output shaft directly connected to the rotatable support, a power input shaft positively connected to the means for withdrawing material from the supply, and a shaft positively connected to said torque motor to drive said torque motor in the reverse of its normal direction of drive.

8. The combination with a rotatable member for holding a supply of strand material and means for withdrawing strand material from said rotatable member, of means for restraining said rotatable support comprising a differential gear mechanism including spider support planet gears, a ring gear meshing with the planet gears and a sun gear meshing with said planet gears, a torque motor positively connected to said sun gear, means positively interconnecting said spider and

the rotatable support, and means positively interconnecting the ring gear with the means for withdrawing the strand material from the rotatable support.

5 9. The combination of a rotatable support member for holding a supply of strand material and means for withdrawing strand material from said rotatable support member, of means for restraining movement of said rotatable support member comprising a differential gear mechanism including a ring gear positively driven in fixed relation to the operation of the means for withdrawing strand material, a pair of planet gears meshing with said ring gear, a spider for rotatably supporting said planet gears and positively connected to said rotatable support, a sun gear meshing with said planet gears, a torque motor positively connected to said sun gear for tending to restrain the rotation of said spider through the action of the planet gears to apply a constant braking force to the rotatable support.

10 10. The combination of a rotatable support member for holding a supply of strand material and means for withdrawing strand material from said rotatable support member, of means for restraining movement of said rotatable support member comprising a differential gear mechanism including a ring gear positively driven in fixed relation to the operation of the means for withdrawing strand material, a pair of planet gears meshing with said ring gear, a spider for rotatably supporting said planet gears and positively connected to said rotatable support, a sun gear meshing with said planet gears, a torque motor positively connected to said sun gear for tending to restrain the rotation of said spider through the action of the planet gears to apply a constant braking force to the rotatable support member comprising a differential gear mechanism including a ring gear positively driven in fixed relation to the operation of the means for withdrawing strand material, a pair of planet gears meshing with said ring gear, a spider for rotatably supporting said planet gears and positively connected to said rotatable support, a sun gear meshing with said planet gears, a torque motor positively connected to said sun gear for tending to restrain the rotation of said spider through the action of the planet gears to apply a constant braking force to the rotatable support, said torque motor consequently being driven in 30 a reverse direction to its normal direction of rotation at a varying speed controlled by the speed of the rotatable support member.
